UNITED STATES PATENT OFFICE.

JOSEPH M. VANOVER, OF TERRE HAUTE, INDIANA.

SLIDING GATE.

SPECIFICATION forming part of Letters Patent No. 448,466, dated March 17, 1891.

Application filed September 15, 1890. Serial No. 365,031. (No model.)

To all whom it may concern:

Be it known that I, JOSEPH M. VANOVER, a citizen of the United States, residing at Terre Haute, in the county of Vigo and State of Indiana, have invented certain new and useful Improvements in Sliding Gates; and I do hereby declare the following to be a full, clear, and exact description of the invention, such as will enable others skilled in the art to which it

appertains to make and use the same.

My invention relates to sliding gates; and it consists in the improved construction and arrangement or combination of parts herein-after fully disclosed in the description, drawings, and claims.

The objects of my invention are to provide an improvement upon the gate for which Letters Patent No. 412,684 were granted to me on the 8th day of October, 1889, whereby the gate may be operated by hand by a person walking, on horseback, or in a carriage or wagon, and to provide improved means for cushioning the shock of the gate upon the gate-supporting posts and the latch-post in opening or closing the gate. These objects are attained by the devices illustrated in the accompanying drawings, forming a part of this specification, in which the same reference-numerals indicate the same parts, and in

which—

Figure 1 represents a perspective view of my improved gate, and Fig. 2 an enlarged detail view of the checking or cushioning device upon the same.

In the drawings, the numeral 1 indicates the gate, which is hung to roll with its top and bottom rails 2 upon rollers 3, journaled upon the faces of the gate-supporting posts 4 and 5, which form a part of the fence. The gate closes against the latch-post 6 at the opposite side of the roadway.

A shaft 7 is vertically journaled in brackets 8 upon the face of the outer gate-supporting post 4, and is formed with a crank 9 at its lower end. A bevel cog-wheel 10 is secured upon said vertical shaft near the upper bracket and meshes with a bevel cog-wheel 11, which is journaled with its shaft 12 upon the face of the gate-supporting post 4. An arm 13 is secured at one end to the end of said shaft 12, and has its other end pivotally connected to the inner end of an arm 14, piv-

oted at its other end to the upper outer corner of the gate-panel in the same manner as illustrated and described in my patent above referred to, so that the gate may be thrown open or closed by rocking or revolving said vertical shaft 7 and the bevel-wheel upon the same, the bevel-wheel 11, and its shaft, the arm 13 drawing or pushing the gate open or closed as it is swung backward or forward.

Two hand-levers 15 are fulcrumed near their lower ends upon two short posts 16, arranged in the ground at the side of the roadway and one on each side of the gate, and the upper longer arms of said levers are of sufficient length and of convenient shape to be grasped and rocked by a person walking, riding, or driving. Two connecting-rods 17 are pivoted to the ends of the short arms of said hand-levers and to the crank 9 upon the vertical shaft 7, so that said shaft may be rocked or partly revolved by tilting said levers.

It is obvious from the foregoing that a person desiring to open or close the gate may do so by tilting or rocking the lever at the side of the gate where he is at the time without being obliged to dismount if he be riding or driving and without the trouble of striking a projecting bail, crank, or lever with the wheel of the vehicle, which often involves considerable difficulty during heavy snow-fall or at night. This opening device will also enable a person walking or riding on horseback to operate the gate with as much ease as a person driving a vehicle.

In sliding gates of this construction in which the gate is quickly rolled back and forth the gate opens and closes with a considerable shock against the gate-supporting posts and against the latch-post, which in time will loosen said posts and cause them and the gate to sag and to fail to open or close properly and perfectly, and for the purpose of checking or cushioning said shocks I apply the device to the gate which I shall now proceed to describe.

A lever 18 is fulcrumed upon the inner or rear stile 19 of the gate-panel and has its lower arm projecting below the lower edge of the gate-panel. A bar 20 is transversely secured upon said stile and has its ends 21 bent at right angles and perforated for the reception of a rod 22, which is pivoted at its middle

to the upper arm of the lever and slides in
said perforated ends. Two coiled springs 23
are wrapped around said rod between the le-
ver and the perforated ends 21. Two stakes
5 24 are driven into the ground at a distance
from each other equal to the throw of the
gate and at points in the line or path of the
gate where they may be struck by the lower
end of said lever 18 when the gate is slid open
10 or closed. Whenever now the gate is slid
open or closed the lower end of the lever 18
will strike one of the stakes 24 at the end of
the stroke or throw of the gate-panel and the
lever will be rocked, compressing the coiled
15 spring upon the rod against which it is tilted,
and the shock of the gate will thus be checked
or cushioned without injuring the posts or the
gate-panel.

Having thus fully described the construc-
20 tion and arrangement or combination of the
several parts of my improved sliding gate, its
operation, and advantages, what I claim as
new is—

1. In a sliding gate, the combination of a
25 lever pivoted upon the gate-panel, springs se-
cured upon said gate-panel and bearing

against both sides of one arm of said lever,
and stops arranged in the path of said gate-
panel to engage said lever at the ends of the
throw or stroke of said panel, substantially as 30
described.

2. In a sliding gate, the combination, with
the gate-panel provided with means for sliding
it open or closed, of the lever 18, pivoted upon
said panel, the transverse bar 20 upon said 35
panel, formed with the bent perforated ends
21, the rod 22 upon the arm of said lever, slid-
ing in said perforated ends, the springs 23
upon said rod, confined between said lever-
arm and perforated ends, and the stakes 24, 40
arranged at a distance from each other equal
to the throw of the gate and in the path of the
same, adapted to be struck by the lower arm
of the lever, substantially as shown, and for
the purpose set forth. 45

In testimony whereof I affix my signature
in presence of two witnesses.

JOSEPH M. VANOVER.
